UNITED STATES PATENT OFFICE

SAMUEL T. THORPE, OF BRISTOL, CONNECTICUT, ASSIGNOR TO THE HORTON MANUFACTURING COMPANY, OF BRISTOL, CONNECTICUT, A CORPORATION OF CONNECTICUT

GOLF CLUB

Application filed May 25, 1931. Serial No. 539,864.

This invention relates to improvements in golf clubs and particularly to a novel arrangement of securing the golf club shaft in the head, especially where the club has a metallic head.

Heretofore, in attaching metal shafts to metal club heads it has been general practice to utilize what is commonly known as an adapter for securing a neat and firm fit or connection between the club shaft and club head. In the present invention, the adapter is likewise used but the primary object of the invention is to provide a novel arrangement for securing the adapter in the club head.

15 A further object is to provide a rigid and firm attachment of the adapter in the club head by means that are rendered operative, so to speak, by the shaft when the latter is inserted in the club head.

20 More particularly, the invention contemplates a club head having a socket therein for the reception of the adapter and club shaft, the wall of said socket being recessed to receive projections formed on the adapter.

25 The portion of the adapter carrying these projections is resilient and expansible. It may be contracted sufficiently to permit its insertion in the socket to a point where its projections will coincide with the recessed portion 30 of the socket wall but when the shaft is inserted in place in the club head it will expand the adapter and force the projections on the latter into the recessed portion of the socket. When thus attached, it is impossible 35 for the adapter to work loose from the socketed portion of the head.

With these and other objects in view, the invention consists in certain details of construction and combinations and arrangements of parts as will hereinafter be more fully described and the novel features thereof particularly pointed out in the appended claims.

In the accompanying drawings—

40 Figure 1 is an elevational view of a golf club, a portion of the shaft being omitted;

Fig. 2 is a longitudinal sectional view of the club assembled;

Fig. 3 is a similar view but with the several elements in the club disassembled, and

45 Fig. 4 is a detail view of the adapter.

In the present instance there is shown a metallic club head 10, having a projecting portion, commonly termed the hosel. This hosel portion has a socket 12 therein, said socket being counterbored, at 12a, to form a shoulder 13 on which the inner end of the adapter 14 seats. A short distance above the shoulder 13 the wall of socket 12 is formed with a recess preferably extending around the entire wall to form the annular indentation, or recess 15.

The adapter 14 is of suitable metal and its end, portion which enters the hosel is cut away to form a longitudinally extending slot 16 emerging into a circumferential slot 17. Preferably, the adapter is slotted in this fashion at two diametrically opposite points. By being thus slotted the end of the adapter may be contracted or expanded somewhat and formed on this expansible portion are one or more projections 18 adapted to register with the annular recess 15 in the socket wall. On its exterior surface, above its slotted portion, the adapter 14 is provided with knurled surfaces 19 for firmly retaining thereon a celluloid sleeve 20, which is utilized to impart a better appearance to the finished club, as otherwise there would be a projection formed in the upper end of the hosel when the sleeve and shaft are in place whereas the celluloid sleeve 20 can be tapered upwardly so as to emerge gradually into the line of the exterior surface of the shaft 21. It might be added that the celluloid sleeve is shrunk on the adapter 14 and by having the knurled surfaces on the adapter, indentations are formed into which portions of the celluloid sleeve are forced so as to securely retain it on the adapter.

In assembling the several structural elements, the adapter 14 with the celluloid sleeve 20 thereon is inserted in the bore of the hosel by slightly contracting its slotted end portion. The projections 18 move into registry with the annular recess 15 and the shaft 21 is then inserted. Before inserting the shaft a ring member 22 is placed thereon and, when the shaft is fully inserted in the club head, this ring member 22 will be firmly wedged on the shaft, the shaft being of tapered for-

mation. At the same time the ring member will have been forced against the upper end of the adapter 14 and the adapter 14 will be positioned against shoulder 13 in the hosel 5 socket. The insertion of the shaft 21 into the club head expands the slotted end of the adapter and forces the projections 18 into the recess 15 and said projections cannot become disengaged from said recess because 10 the presence of the shaft within the adapter maintains the slotted end portion expanded. To prevent withdrawal of the shaft, or to securely attach it within the socket, it is provided with the usual rivet 23 extending 15 through the hosel and the inner end portion of the shaft 21. With this arrangement, it will be seen that it is absolutely impossible for the shaft 21 to be displaced because of the rivet 23 and, it being impossible for the shaft 20 to be removed, it is also impossible for the adapter to be accidentally displaced because the presence of the shaft prevents the contraction of the slotted portion of the adapter as is necessary to release the projections 18 25 from the recess 15. These projections 18 and recess 15 may be broadly described as constituting interlocking elements carried by the adapter and club head and, while it is not necessary that these elements be formed exactly as shown, it is preferred that the projections 18 be provided on the adapter and the recess be provided in the hosel.

What I claim is:

1. A golf club comprising a head having 35 a socket therein, an adapter extending into said socket, a shaft projecting into said adapter and socket, and interlocking elements formed on said adapter and socket, said elements being held in interlocking engagement by the shaft.

2. A golf club comprising a head having a socket therein, a sleevelike, radially expandable adapter extending into the socket, interlocking elements formed on said adapter 45 and the wall of the socket, and a shaft extending into said adapter and socket and radially expanding the adapter to lock said interlocking elements in engagement with each other.

50 3. A golf club comprising a head having a socket therein with a recess in the wall of said socket, a sleevelike adapter, a projection on said adapter adapted to enter said recess, and a shaft extending into the adapter 55 and socket and locking said projection in said recess.

4. A golf club comprising a head having a socket therein and an annular recess in the wall of said socket, an adapter extending 60 into said socket, a plurality of projections on said adapter engageable in said recess, and a shaft extending into said adapter and socket, said shaft forcing said projections into said recess.

65 5. A golf club comprising a head having a

socket therein with a recess in the wall of said socket, a metallic tubular adapter extending into said socket, the end portion of the adapter in the socket having a slit therein to permit said portion to be expanded, a 70 projection on said end portion adapted to engage in said recess, and a shaft extending into said adapter, said shaft expanding the adapter and locking said projection in said recess.
